ADOLPH PETZOLD, OF PHILADELPHIA, PENNSYLVANIA.

DESIGN FOR A RUG.

Design No. 16,192, dated August 4, 1885.

UNITED STATES PATENT OFFICE.

ADOLPH PETZOLD, OF PHILADELPHIA, PENNSYLVANIA.

DESIGN FOR A RUG.

SPECIFICATION forming part of Design No. 16,192, dated August 4, 1885.

Application filed April 11, 1885. Term of patent 3½ years.

To all whom it may concern:

Be it known that I, ADOLPH PETZOLD, a citizen of the United States, and a resident of Philadelphia, Pennsylvania, have invented and produced a new and original Design for a Rug, of which the following is a specification, reference being had to the accompanying photographic illustration, to which reference is made.

10 The accompanying illustration represents my design for a rug, with one of the end panels omitted, the one so omitted being a duplicate of the end panel shown.

The design consists of an outer broad border, A, a middle oval panel, B, and two end panels, one of which is shown lettered C. The middle panel, B, is ornamented with a large cluster of dark leaves, E, curved twigs F, and fanciful flowers G H I in the foreground, and 20 lighter-tinted leaves K in the background. (See illustration.) The leaves are of various designs in graceful forms. The end panels, C,

are bounded or inclosed by curved branches L L, scrolls M M, and leaf-scrolls N N. Each end panel is ornamented by the flowers O O' 25 O" upon diverging branches P P, joining each other at Q, and leaves R R.

The leading features of my design are, the outer broad border, A, middle oval panel, B, ornamented with leaves, flowers, and twigs, as 30 shown, and the end panels, C, bounded by the curves and scrolls shown and described, and ornamented with leaves and flowers upon branches P P, diverging, as shown, from the point Q.

What I claim as new is—

The design for a rug, substantially as shown and described.

ADOLPH PETZOLD.
